DESIGN FOR A SPECTACLE FRAME

Raymond L. Wells, Attleboro, Mass., assignor
to American Optical Company, Southbridge,
Mass., a voluntary association of Massachusetts

Application September 29, 1949, Serial No. 5,210

Term of patent 14 years

(Cl. D57—1)

To all whom it may concern:

Be it known that I, Raymond L. Wells, a citizen of the United States of America, residing at Attleboro, in the county of Bristol and State of Massachusetts, have invented a new, original, and ornamental Design for a Spectacle Frame, of which the following is a specification, reference being made to the accompanying drawings, forming a part thereof.

Fig. 1 is a perspective view of a spectacle frame; and

Fig. 2 is a side elevational view thereof on a slightly enlarged scale, showing the essential features of my design in full lines.

I claim:

The ornamental design for a spectacle frame, substantially as shown and described.

RAYMOND L. WELLS.
